CLAIM

I claim the ornamental design for a treble hook, as shown and described.

DESCRIPTION

FIG. 1 is a front view of a treble hook, showing my new design:

FIG. 2 is a back view thereof;

FIG. 3 is a side view thereof;

FIG. 4 is another side view thereof;

FIG. 5 is a top view thereof; and,

FIG. 6 is a bottom view thereof.

1 Claim, 4 Drawing Sheets
